M. S. STORER,
BRICK KILN
APPLICATION FILED MAR. 7, 1904.

2 SHEETS—SHEET 2.

UNITED STATES PATENT OFFICE.

MARCELLUS S. STORER, OF NELSON, NEBRASKA.

BRICK-KILN.

SPECIFICATION forming part of Letters Patent No. 789,577, dated May 9, 1905.

Application filed March 7, 1904. Serial No. 197,020.

To all whom it may concern:

Be it known that I, MARCELLUS S. STORER, a citizen of the United States, residing at Nelson, in the county of Nuckolls and State of Nebraska, have invented a new and useful Brick-Kiln, of which the following is a specification.

This invention relates to brick-kilns, and more especially to the arrangement of the flues or passages within the kiln.

10 The principal object of the invention is to provide a system of furnaces and channels for the generation and distribution of the heat and products of combustion through a charge of green brick in such manner as to insure the even and uniform burning of the entire charge, so producing throughout the entire charge brick of similar color and hardness.

15 A further object of the invention is to provide a system of flues or passages for the distribution of heat and the products of combustion through the charge of green brick in such manner as to effect the most economical use of the fuel.

With the objects above mentioned and others 20 in view my invention consists in the novel features of construction and arrangement of furnaces and channels in brick-kilns, as herein-after fully described and claimed, and illustrated in several different forms of embodiment in the accompanying drawings.

25 The invention is readily applicable to kilns of any of the ordinary forms, whether round, square, or elongated, and in order to make the invention clearly understood I shall describe its embodiment in kilns of the round and elongated forms.

In the drawings, Figure 1 is a horizontal sectional view through the side wall of a kiln and a portion of the charge of brick therein 30 upon the line 1 1 of Fig. 2. Fig. 2 is a vertical section on the line 2 2 of Fig. 1. Fig. 3 is a vertical longitudinal section through a portion of the kiln on the line 3 3 of Fig. 1. Fig. 4 is a horizontal section on the line 4 4 of Fig. 5, showing the arrangement of flues in a "beehive" kiln. Fig. 5 is a vertical longitudinal section on the line 5 5 of Fig. 4. Fig. 6 is a vertical longitudinal section on the line 6 6 of Fig. 4.

35 Referring to the drawings, in which corre-

sponding parts are designated by similar characters of reference throughout, and having reference more particularly to Figs. 1 and 2, 1 1 represent the vertical side walls of the kiln, outside of which are arranged batteries 55 of fire-boxes or furnaces 2 and 3, the former of which are updraft and the latter downdraft furnaces. B designates generally the charge or "clamp" of green brick, arranged within the kiln upon the floor F thereof, and C designates the crown or top of the kiln. In the structure shown in Figs. 1 and 2 the charge B is formed with channels extending transversely thereof from each fire-box or furnace to a tunnel extending longitudinally of the 65 kiln along the median line and leading to a smoke-stack disposed external to the kiln at a suitable distance therefrom in order to produce the requisite amount of draft. The tunnel, which is designated 4, will vary in dimensions according to the size of the kiln, and the channels which lead thereto from the furnaces are of two sizes. The channels leading from the furnaces 2 are wider than those leading from the furnaces 3, the wider channels being preferably about fourteen inches in width and the narrower ones about eight inches in width and the channels being in both instances about twenty-four inches deep. The wider channels, which are designated 5, 70 are as wide as the furnaces from which they lead, but the narrower channels (designated 6) are narrower than the furnaces from which they lead, and vertically-arranged bag-walls 7 are provided at the ends of the furnaces of 75 these latter channels for purposes that will presently be explained. The bag-walls 7 extend vertically upward to the top of the charge B of green brick and afford passages between the charge of brick and the side 80 walls along which the products of combustion may rise to the top of the kiln. Small openings 8 are provided at intervals in the sides of the bag-walls 7 to permit the products of combustion to pass therethrough into 85 the spaces between the green bricks constituting the charge of the kiln.

The charge of brick is arranged in the usual manner over the floor of the kiln, spaces being left between individual bricks, as shown, 90

in order to permit free circulation of the currents bearing the products of combustion. Above the channels 5 and 6 the brick are laid so as to form arches, as shown at 9 in Fig. 3, 5 and at the top of the kiln some space is left between the charge of brick and the crown of the kiln to permit the currents to pass horizontally over the sides of the charge of brick toward the middle thereof before being drawn 10 downward to the tunnel below the brick.

When the kiln is in operation, the heat from the furnaces 2 and 3 of each battery will set up currents which pass inward from the furnaces and ultimately reach the tunnel leading 15 to the stack. The products of combustion from the furnaces 2 of each battery pass directly along the channels 5 toward the tunnel; but the loosely-laid brick of the charge above the channels 5 afford passages upward, into 20 which the products of combustion are drawn to a certain extent, as the said products of combustion are necessarily lighter than the cool gases higher up in the kiln, and convection currents are necessarily produced in 25 sequence. The currents which pass inward from the furnaces 3 of each series are checked in part when they reach the bag-walls 7, and a considerable percentage of the products of combustion there are carried upward by convection in the bag-walls 7, while the remainder 30 will pass toward the tunnel along the channels 6. Upward currents in the bag-walls 7 are reduced as they rise by losses which take place through the small openings 8, leading 35 into the spaces between the green bricks of the charge; but the residue of the said currents pass upward to the top of the kiln, strike against the crown thereof, and are deflected downward and toward the middle of 40 the kiln. After being deflected downward the currents which pass upward in the bag-walls 7 are caused to find their way to the tunnel 4 by passing through the charge of green brick. In passing downward to the 45 tunnel 4 the currents from the top of the kiln mingle with those that work their way through the small openings 8 in the sides of the bag-walls 7 and also become mingled with the upward currents from the channels 6. 50 As the crown of the kiln is either constructed without openings or else the openings therein are tightly closed, the general direction of the current passing out of the kiln is downward to the tunnel 4 and thence to the stack S. In 55 producing the single general current that sweeps from the kiln through the tunnel 4 all of the separate currents which enter from the furnaces are combined. Consequently the upward currents from the channels 5 blend 60 with the horizontal currents through the openings 8 and with the downward currents from the crown of the kiln. In this way the heat from the furnaces is so disseminated through the entire charge or clamp of green brick 65 that a gradual heating of the entire mass of

green brick is brought about without at any time producing excessive temperatures in any part of the whole mass. In this way the destruction of a considerable quantity of brick by overfiring, which is of frequent occurrence 70 when the bricks are exposed directly to the heat of the fires, is avoided. Instead the bricks in all parts of the kiln heat at nearly the same rate, and it is unnecessary in order to obtain the requisite degree of heat in one 75 part of the kiln to heat the bricks excessively in another part.

In Figs. 4 to 6 I have illustrated an embodiment of the invention in a round kiln, in which a charge of green brick is arranged in 80 a manner similar to that already explained in connection with an elongated rectangular kiln.

In Figs. 4 to 6, F' designates the floor of the kiln; C, the crown; 20, the side walls; 21, the updraft and 22 the downdraft furnaces, and 85 23 the underground flue or tunnel leading from the center of the kiln to the stack. In this form of kiln the furnaces are arranged peripherally, as shown, and the furnaces 21 and 22 alternate in position in somewhat the 90 same manner as the furnaces 2 and 3 in the form of kiln already described. Comparatively wide channels 24 extend from the furnaces 21 toward the center of the kiln, where they communicate with the tunnel 23. Narrower channels 25 are arranged similarly between the furnaces 22 and the center of the kiln. These narrower channels extend from vertically-arranged bag-walls 26, which extend upward toward the crown of the kiln. 95 The bag-walls 26 are provided with openings 27 in the inner sides thereof to permit currents to pass from the bag-walls 26 into the spaces left in the charge of green brick, and at the top of the kiln the currents which pass 100 upward along the vertical bag-walls are deflected inward and downward, so that they may pass downward through the interstices in the charge of brick to the tunnel at the center of the kiln. The charge or clamp of 105 green brick is disposed in the kiln in such manner as to present enough open space therein for the ready passage of the currents of heated air and smoke, and arches 28 are formed in the lower part of the charge over the channels 110 24 and 25, so affording means for the currents sweeping inward along said channels to rise and become distributed through the lower part of the mass of brick. At the central 115 part of the charge over the end of the underground flue 23 the green brick are arranged in as open order as possible to facilitate the passage downward of the heated air and smoke from the crown of the kiln structure. In order to afford sufficient support for the 120 central portion of the charge when constructed in this manner, it is necessary to provide piers 29 in the end of the tunnel and to rest the central portion of the charge of brick upon these piers, as shown in Fig. 5. With 125 130

the charge or clamp of green brick arranged and supported in this manner the circulation of the currents of heated air and products of combustion throughout the entire mass of green brick in the desired manner is insured, the currents sweeping inward along the channels 24 and 25 passing downward into the tunnel through the spaces external to the piers 29 and the downward currents through the center of the charge moving through the spaces surrounded by the piers. In this form of the invention, as in that already described, the outflow of the products of combustion from the kiln must take place through the underground flue or tunnel 23 to the stack, and consequently the several currents above mentioned—the upward currents, the bottom currents, and the currents introduced into the charge of brick from the sides—all combine to produce a single resultant current in the underground flue or tunnel 23, the strength of this current being determined by the size and length of the tunnel, the dimensions of the stack, and the arrangement of the bricks within the kiln.

While I have described the invention as embodied in only two different forms of kiln, it is obvious that other forms of kiln are susceptible of arrangement in similar manner, and it is also obvious that the channels described in the foregoing paragraphs as formed in the charge of brick instead of in the permanent structure thereof might be as readily formed in the permanent kiln structure. Furthermore, it is not necessary that the arches be formed of the green brick over said channels, as permanent arches with openings therein may be employed, if preferred. It is quite obvious that the wall constituting the sides of the vertical bag-walls in the two different forms of kiln need not be made of fire-brick, but may be constructed of green brick suitably laid and serve all the purposes of this invention.

Inasmuch as the gist of the present invention lies in the mode of distributing the cur-

rents bearing the heat from the furnaces through the green brick in the kiln in order to produce uniform effects in burning, the green brick and the permanent kiln structure form for the purposes of this invention a single or unitary structure and the passages in the permanent kiln structure and in the charge of green brick coöperate in effecting the results contemplated in this invention.

Having thus described the construction and use of my invention, what I claim as new, and desire to secure by Letters Patent, is—

1. The combination with a kiln, of a stack external thereto, a tunnel leading to the stack and having an inlet-opening in the middle of the floor of the kiln, updraft and downdraft furnaces arranged alternately at the sides of the kiln, and channels connecting the furnaces with the tunnel.

2. The combination with a kiln, of a stack external thereto, a channel beneath the floor of the kiln and leading to the stack, and having an inlet-opening at the middle of the floor, updraft and downdraft furnaces arranged alternately at the sides of the kiln, channels leading from the furnaces to the center of the kiln, and bag-walls disposed within the kiln in front of the downdraft-furnaces.

3. The combination with a kiln, of a stack external thereto, a channel beneath the floor of the kiln and leading to the stack, and having an inlet-opening at the middle of the floor, updraft and downdraft furnaces arranged alternately at the sides of the kiln, channels leading from the furnaces to the center of the kiln, and bag-walls provided with laterally-discharging openings and disposed within the kiln in front of the downdraft-furnaces.

In testimony that I claim the foregoing as my own I have hereto affixed my signature in the presence of two witnesses.

MARCELLUS S. STORER.
